BY

UNITED STATES PATENT OFFICE.

GEORGE S. BOWMAN, OF LEBANON, PENNSYLVANIA.

KNOCKDOWN PACKAGE.

1,144,633.

Specification of Letters Patent. Patented June 29, 1915.

Application filed December 9, 1913. Serial No. 805,545.

To all whom it may concern:

Be it known that I, GEORGE S. BOWMAN, a citizen of the United States, and a resident of the city and county of Lebanon, in the 5 State of Pennsylvania, have invented certain new and useful Improvements in Knockdown Packages, of which the following is a specification.

My invention relates to improvements in 10 knockdown packages, and more particularly to improvements in the package for which Letters Patent of the United States were issued to me on November 11, 1913, No. 1,078,245, the object of my present invention 15 being to simplify, cheapen and improve the package set forth in this patent.

My invention is illustrated in the accompanying drawings, which form part of this specification, in which similar letters of reference indicate similar parts throughout the 20 several views, and in which—

Figure 1, is a plan of part of the body of the package, the sides of which are shown bent over to form channels to receive the 25 tongues carried by the head, and which is cut and struck out to form keepers for a locking pin: Fig. 2, a side elevation of the completed package one end of which is furnished with a head and the other end of which is open: Fig. 3, a top view of Fig. 2: Fig. 4, a section of Fig. 3 on line A—A: Fig. 5, a plan of blank from which the heads may be struck: Fig. 6, a plan of head formed from blank shown in Fig. 5: Fig. 7, 35 a plan of inside of blank for forming the body: Fig. 8, a top view of Fig. 7.

The body 1 of my improved package is formed from a flat sheet of material the opposite edges of which are bent over outwardly, to form channels 2, each channel having a lateral opening or openings 15. The body, or blank, 1 may be of a great length and cut off as may be required to form cylindrical bodies of any diameter. 45 The bodies are formed by bending the sheet 1 into cylindrical form, its ends overlapping one another as shown in Figs. 2 and 3. Near its ends each end of the sheet 1 is cut at 3—4 and between these cuts struck inwardly to form pockets 5—6 which, when the body is bent to cylindrical form, rest one within the other and are adapted to receive a pin or key 7 which securely but detachably, locks the two ends of the body together.

55 Heads 20 are provided for closing the opposite ends of the body 1. Each of these

heads is composed of a closing disk and a wide or deep band 21 connected therewith preferably in the form of a flange thereof. This wide or deep band or flange is adapted 60 to surround the narrow out-turned flange 2 of the body 1 and to extend beyond the edge thereof. The wide band or flange is provided with one or more tongues 9 cut from the body of the flange or band 21, preferably on a curved line as shown at 8 in Fig. 2. This tongue is attached at its base to said wide band or flange at a point beyond the edge of the body flange 2 at a point between the edges of the body flange 2 and the flange 70 or band 21. This tongue projects toward the head and has a free end which extends beyond the edge of the body flange 2 into the channel formed thereby. The heads are 75 rotatable on the body to cause the tongues to engage or disengage said channel through the lateral openings 15 in the body flange 2.

When the heads are placed over the ends of the body and rotarily turned the tongues 9 successively enter the open end of the 80 channel 2. If the head be turned so as to make a complete revolution the first tongue to enter the channel will engage the outer end 10 of the body 1 and the turning of the head in this direction will be stopped. The 85 heads may be locked in position by simply bending the lower edge of the channel 2 outwardly as shown in Fig. 5 so as to engage the sides of the cuts forming the tongues.

The heads may be formed in any convenient manner. In Figs. 5 and 6 a head struck from a square piece of material is shown. The corners of this square piece are first folded over, as shown in Fig. 5, to form an octagonal blank and this is then 95 struck out, as shown in Fig. 6, to form a substantially round head with a flange which is afterward cut to form the tongues for engaging the channels on the body. The necessary folding of the octagonal blank to 100 form the flange of the head greatly strengthens this structure and fits it for any rough usage without danger of breaking it.

Having thus described my invention I claim as new and desire to secure by Letters Patent:—

A receptacle comprising a cylindrical body provided with an outward narrow flange forming a channel between it and said body at one end thereof, said flange having a lateral opening, a head for closing an end of said body provided with a band of greater

depth than said flange and adapted to surround and extend beyond said body flange, said head band having a tongue which is connected therewith at a point between the edges of said head band and said body flange and which has a free end projecting toward said head to a point beyond the edge of said body flange and into the channel

formed thereby, and said head being rotatable on said body to cause said tongue to engage or disengage said channel through said lateral opening in said body flange.

GEORGE S. BOWMAN.
